CHECK-WRITING MACHINE.

1,302,244.

Specification of Letters Patent. Patented Apr. 29, 1919.

Application filed August 24, 1916. Serial No. 116,661.

To all whom it may concern:

Be it known that I, CHARLES G. TIEFEL, of Rochester, in the county of Monroe and State of New York, have invented certain new and useful Improvements in Check-Writing Machines; and I do hereby declare the following to be a full, clear, and exact description of the same, such as will enable any person skilled in the art to which the invention appertains to make and use the same.

This invention relates to printing machines of the hand stamp variety commonly used for marking checks and other instruments with their monetary value, or other inscription, and known as "check writers".

One object of the invention is the provision of a convenient machine of the class described having a plurality of type forms representing a wide range of words suitable, by selective combination, for printing upon a check or other instrument, any desired monetary value, or other legend, and as the words are of various lengths, means is supplied for feeding the work after each impression a variable distance corresponding to the length of the word printed.

Another object is the provision of a machine of this variety complete in function yet simple and economical in construction and employing a minimum number of parts.

A further object is to provide various improvements in the details of construction of the operating mechanism, contributing to the utility of the machine. These and other objects and advantages are fully set forth in the following detailed description of one embodiment of the invention selected for the purpose of illustration and shown in the accompanying drawings, in which:

Figure 1 is an elevation of the machine as seen from the front, with a portion of the casing broken away to show the type wheel.

Fig. 2 is a vertical sectional view on the line 2—2 of Fig. 1, looking in the direction of the arrow, showing the parts in normal position.

Fig. 3 is a plan view of the machine in section, taken on the line 3—3 of Fig. 1, showing the parts in normal position.

Fig. 4 is a bottom plan view of the machine showing the position of the parts during an impression.

Fig. 5 is a detail sectional view of the operating crank, with its full stroke mechanism in operation.

Fig. 6 is a detail sectional view of the pawl and ratchet device of the work feeding mechanism, taken on the line 6—6 of Fig. 2, looking in the direction of the arrow.

The present invention comprises a machine having a casing for supporting and inclosing the operating parts, indicated generally by the reference numeral 10. This casing has a base portion 11 having a bed 12 (Fig. 2) adapted to receive and support the work, and overhanging this bed or work support is an upper portion 13 of the casing, a slot 14 being left between the upper and lower portions of the casing and above the printing bed 12, to permit of the location of the work on the printing bed.

In the upper portion of the casing is a type carrier 15 preferably in the form of a cylinder or drum, having a hub 16 (Figs. 2 and 3) which is fitted up and secured by means of a pin 17 to shaft 18 journaled at its ends in the walls of the casing. One end of this shaft is slotted, and the plate 19 (Fig. 3) is provided with an aperture, the edges of which are adapted to be slipped into engagement with the slot in the shaft, the plate being then secured to the exterior wall of the casing so that it prevents end-wise movement of the shaft in its bearing. The type carrier has fixed on its periphery, or integrally formed therewith, a type plate 20 bearing a plurality of type forms or printing characters 21 extending parallel with the axis of the carrier and spaced from each other circumferentially thereof, these type forms all having their beginnings in a common line extending circumferentially of the carrier in a plane perpendicular to its axis, as shown in Fig. 1. With this arrangement the type forms 21 may be brought individually and selectively to printing position at the lower side of the wheel adjacent the work by rotational adjustment of the shaft 18, for which purpose the latter has fixed to its end exteriorly of the casing a knob or finger piece 22. For the purpose of indicating the type form in printing position there is provided a dial wheel 23 having marked upon its periphery a series of numerals and other symbols

95
100
105

shown in Fig. 1, and coöperating with this dial are a pair of index fingers 24 fixed on the casing of the machine in position to extend over the dial and to inclose between them one of the symbols on the wheel 23. The arrangement of the type forms on the carrier and of the symbols on the dial is such that when the knob 22 is rotated to bring one of the symbols between the index fingers 24, the type form for printing this symbol upon the work is brought to printing position at the lower side of the wheel.

The type forms on the carrier represent a series of words of various lengths expressing the amounts from 1 to 19 inclusive, the multiples of 10 from 20 to 90 inclusive, the words "Hundred," "Thousand," "Dollars" and "Cents," as well as a star, or other conventional character used as a limiting mark to stop off the end of a line of writing. By selective combination of these words any exact amount of dollars and cents up to one million dollars may be written on the check. The star or other conventional character referred to is commonly placed at the beginning of the amount to prevent its alteration by the prefixing of one or more words, and the words "Dollars" and "Cents" are placed at the ends of their respective amounts to prevent the alteration of the amount for which the check is drawn by the suffixing of one or more words. By expressing the amount in words instead of in figures, the difficulty of alteration of the inscription is obviously increased because the alteration of each digit of the amount necessitates the alteration of a word comprising several letters instead of a single figure. The invention, however, may of course be employed to print legends and inscriptions other than monetary values as described.

The platen for pressing the work against the type to secure an imprint therefrom comprises a bar 25 (Figs. 2 and 4) having on its top an impression surface slightly wider than the height of a type form and longer than the longest word to be printed. The impression surfaces of the platen and type may, if desired, be formed with corrugations or serrations arranged to register and co-operate with each other during the impression so as to disrupt or shred the fibers of the paper at the time that the printing ink is applied, so that the latter may be readily absorbed by the paper. This latter construction is fully disclosed in U. S. Letters Patent 793,249 to Libanus M. Todd, granted June 27, 1905, for an improvement in printing apparatus, so that further description thereof herein is unnecessary. The platen bar 25 is carried on the forward end of a spring plate 26 secured at 27 to the base of the casing, the resilience of the plate 26 serving to normally retract the platen into

lowered position below the printing bed. For raising the platen and thereby raising the work against the type there is provided a lever 28 pinned to a shaft 29 journaled at its ends in the base of the casing, and the lever 70 has a rearwardly extending arm 30 in which is an adjustable screw 31 adapted for contact with the bottom of the platen bar to raise the latter when the lever is turned about its shaft 29. The lever has a forwardly extending arm 32 at the end of which is rotatably carried a roller 33 in position to engage with a cam 34 fixed on a sleeve 35 (Fig. 4) which in turn is fixed to a rock shaft 36, the latter having its ends 80 journaled in the walls of the upper portion of the casing. It will be seen that when the shaft 36 is rocked so as to bring the projecting portion of cam 34 into engagement with the roller 33 of the platen lever, the latter 85 will be rocked and will raise the platen to form an impression. The means for rocking shaft 36 comprises a crank arm 37 fixed on the end of the shaft exteriorly of the casing and carrying a handle 38 conveniently 90 arranged for manual operation. The printing bed has an aperture 39 to permit the raising of the platen therethrough for engagement with the work.

A full stroke mechanism is provided for 95 crank 37 comprising a toothed sector 40 on the crank 37 (Fig. 5) and a coacting finger 41 on a hub 42 rotatably mounted on a pin 43 fixed in the wall of the casing. The hub 42 is provided with an arm 44 to which is 100 attached a spring 45 fixed at its other end to the casing, the spring serving to urge the finger 41 into the path of movement of the toothed sector 40. The construction and arrangement of these parts are such that when 105 the movement of the crank 37 is begun in one direction, the finger or pawl 41 engaging the toothed sector prevents the movement of the crank in the opposite direction until the sector is moved far enough to allow the 110 finger to escape out of contact with it at its end. The direction of motion of the crank may then be reversed when the finger co-acts with the teeth of the sector in a reversed manner so as to insure completion of this 115 second stroke of the crank. As the printing impression requires some pressure on the crank handle 38, an operator might think that a full impression had been made upon the work before the paper was thoroughly 120 shredded by the type and platen, and it is therefore the function of this mechanism to insure the full operation of the crank during an impression in order to produce a thorough shredding and inking of the paper. 125

The means for centering a selected type form precisely in position for coöperation with the platen comprises, preferably, a socket 46 adjustably carried in the wall of the casing and having projecting slightly 130

from its inner end a spring pressed pawl or other member adapted to engage yieldingly in sockets 47 formed in the adjacent end of the type carrier, so that while the carrier 5 may be freely rotated by means of the knob 22, as the type form is brought to printing position, the centering pawl will drop into a corresponding recess 47 and thus urge the type form into its precise printing position.

10 The means for feeding the work between successive impressions of the type comprises a pair of feed rolls 48 fixed on a shaft 49 journaled at its ends in the sides of the casing. As best shown in Figs. 2 and 3, this 15 shaft extends at right angles to the axis of the type carrier, and at such an elevation that the feeding rolls 48 are at their bottoms slightly above the printing bed. In order to raise the work from below and press it 20 against these feed rolls there is provided a corresponding pair of presser rolls 50 journaled on an arm 51 fixed on the shaft 52 below the printing bed, the shaft being rockably supported in the casing and extending 25 exteriorly thereof at the front of the machine where the end of the shaft is formed into an arm 53 adapted to be depressed by the finger so as to rock the shaft 52 and thereby lower the presser rolls 50. The arm 30 51 is provided with a lug 54 to which is attached at one end a tension spring 55 having its other end attached to the casing, this spring acting to rock the shaft 52 so as to raise the presser rolls against the feed rolls, 35 the printing bed being provided with openings through which the presser rolls may be thus projected. The stop pin 56 is provided for limiting the downward movement of the finger piece 53. When it is desired to insert 40 a piece of work the presser rolls are withdrawn by depression of the finger piece 53, after which the work may be freely inserted in the slot 14 of the casing, the piece 53 being then allowed to rise so that the work is 45 held in contact with the feeding rolls ready for a printing operation.

The feed rolls are actuated by a mechanism which includes a ratchet wheel 57 (Figs. 2 and 6) fixed on the hub of the adjacent feed roll, and coöperating with this wheel are four pawls 58 pivotally carried by a yoke 59 fixed on a sleeve 60 rotatably supported on the shaft 49 (see Fig. 2). The pawls 58 are pressed into contact with the ratchet wheel by means of springs 61 supported at 62 on the plate 59, and the sleeve 60 has fixed thereon a pinion 63 with which is adapted to mesh from above a rack 64 formed on the lower side of contact rod 65 which is slidably supported in a lug 66 (Fig. 3) depending from a support or arm 67 projecting substantially horizontally from a reciprocating device or shuttle 68 slidably supported on the shaft 36. The shuttle 68 65 comprises spaced end brackets 69 having a

sliding bearing on the shaft 36 and a central cylindrical wall 69^a connecting these brackets, in which wall is formed a spiral cam slot 70. Engaging the slot 70 is a bearing roller 71 on a pin 72 projecting normally 70 from the shaft 36. The construction and arrangement of these parts is such that when the shaft 36 is rocked by turning the crank 37 first in a clockwise and then in a counter-clockwise direction as seen in Fig. 2, the 75 shuttle 68 and arm 67 are reciprocated along the shaft 36 toward and from the type carrier. The arm 67 is supported from below by the engagement of the rack 64 of the rod 65 with the pinion 63, and is held against upward movement by the engagement of an adjustable stud 74 on a lug 73 on the arm 67 with the under side of shaft 18.

The rod 65 is provided with a projecting pin 75 having attached thereto one end of a tension spring 76, the other end of which is attached to a pin projecting from a lug 76^a on the arm 67. Spring 76 forces the rod 65 yieldably in the direction of the type carrier, which movement is normally limited by the 80 contact of the pin 75 on the rod with the arm 67 so that movement of the arm 67 away from the type carrier imparts a positive movement in the same direction to the rod 65, which, therefore, by the reciprocation of the shuttle 68 is moved yieldably toward the type wheel and positively in the opposite direction.

The type cylinder or drum 15 is hollow, and open at the end on the side of the rod 65, and within the drum on the radial wall on the latter there is provided a gage member comprising a series of stop shoulders 77 extending variable distances in a horizontal direction parallel with the axis of the drum. There is one of these stop shoulders for each character on the type carrier, and as the type characters are of varying length these stop shoulders vary in horizontal extent, the extent of each shoulder being inversely proportional to the length of the corresponding type form, so that a long type form is represented by a short stop shoulder, and vice versa.

The rod 65 extends within the hollow type 115 drum and its end is opposite the path of movement of the stop shoulders during the rotation of the type drum. The stop shoulders are so arranged relatively to their corresponding type forms that when a type form is selected and brought to printing position above the platen the corresponding stop shoulder is opposite the end of rod 65 in position for contact with the latter upon the manipulation of the crank handle 38 and 120 the consequent reciprocation of the shuttle 68. When the contact rod 65 is actuated by the shuttle toward the type drum it imparts an idle rotation to the pinion 63 and the yoke 59 in a clockwise direction, as seen in Fig. 6, 125 130

until the rod strikes the stop shoulder, when the spring 76 begins to yield and the rod is brought to rest. Thus no motion is imparted to the feed rolls during this movement. 5 Upon return of the shuttle 68, however, after the printing impression, arm 67 strikes pin 75 and moves the rod 65 positively away from the type drum. During this movement, the rod 65 rotates the pinion 63 and the 10 yoke 59 in a counterclockwise direction, as seen in Fig. 6, and the pawls 58 engage and turn the ratchet wheel 57, thereby rotating the shaft 49 and the feed rolls 48, feeding the work through the machine from right to left. It will thus be seen that the extent of 15 movement of the contact rod 65, and consequently the extent of rotation of the feed rolls is controlled by the length of the stop shoulder on the gage so as to impart a proper 20 feeding movement to the feed rolls.

In order to prevent reverse movement of the feeding roll and to restrain excessive movement thereof in the feeding direction, due to inertia, a retarding device is provided 25 comprising, preferably, as shown in Fig. 2, a disk 78 fixed on the shaft 49, and a spring friction plate 79 fixed to the casing and bearing resiliently upon the disk 78 so as to frictionally retard rotation of the 30 shaft 49.

The means for inking the type characters comprises, preferably, an inking roll 80 (Fig. 2) journaled at its ends in a pair of arms 81 which are pivotally supported at 35 82 on a bracket 83 fixed to and projecting inwardly from a plate 84 on the exterior of the casing. The casing is provided at this point with an opening indicated at 85, sufficient in size to permit the removal of the 40 inking roll and its supports from the casing, and the supporting plate 84 is pivoted at 85^a at its lower edge to the casing, so that by swinging the top of plate 84 outwardly from the casing the inking roll 80 may be removed 45 for reinking or cleaning. A spring 86 bearing against the bracket 83 and the ink roll arms 81 serves to urge the ink roll away from the plate 84 and against the type wheel so as to ink the characters during the 50 rotation of the type wheel in selecting the type to be printed. It will be noted that the point of contact between the inking roll and type carrier is well below the line of centers of the type carrier and the pivotal support 55 of the plate 84, the result of which arrangement being that the spring actuation of the inking roll toward the type and platen serves to urge the plate 84 inwardly against the casing, holding the ink roll and its supporting 60 plate 84 in position without any necessity for a latch or other fastening means. An additional inking roll 87 is provided, and is shown as journaled at its ends in a pair of arms 88 pivotally supported at 89 on 65 the plate 90, a spring 91 being provided to

urge the roll into contact with the type carrier. The casing is provided in this locality with an opening 92 through which the inking roll may be removed, and the plate 90 is supported in its place over this opening by 70 fingers 93 engaging over the lower edge of the opening 92, and also by a latch 94 engaging under the upper edge of the opening 92 and controlled by the finger piece 95. By turning finger piece 95 latch 94 is disengaged from the casing, and the plate 90 with its attached ink roll may be moved. 75

Extending above the work receiving slot 14 beneath the type carrier so as to protect the work from being smeared with ink by 80 the latter, is provided a guard plate 96, (Fig. 2) supported at 97 on the walls of the casing, and this plate is provided with openings 97^a and 97^b to permit the platen to carry the work into contact with the type forms and 85 also to permit the feeding rolls 48 to engage the work from above.

The means for gaging the location of the work in the machine is shown as comprising, 90 preferably, a plate strip 98 extending across the work supporting bed below the latter, and provided with upwardly extending fingers 99 for engagement with the work. These fingers 99 project above the printing bed through openings 100 in the latter, and are adapted to be adjusted backward or forward for determining the proper location of the work in the machine by means of a corresponding adjustment of the plate 98 which has a rearwardly extending portion 101 provided at the rear side of the printing bed with a finger piece 102 by means of which 95 the gage is adjusted. 100

The operation of the machine will be understood from the above description of its 105 construction. The work gage having been adjusted to suit the size of a check or other piece of paper upon which the printing is to be done, the finger piece 53 is depressed and the work inserted in the machine. By means of the knob 22 and dial wheel 23 the type carrier is adjusted to bring to printing position the first character desired to be printed. The crank handle 38 is then rotated rearwardly and returned to normal position, which movement prints the selected character upon the paper and subsequently feeds the latter a distance proportional to the length of the character printed plus a slight additional distance to provide for the 110 spacing between adjacent words. The type carrier is then rotated to select the next character to be printed, after which the crank handle 38 is again actuated, and so on until the complete legend has been printed 115 upon the paper. During these operations the paper has been fed over the printing bed from right to left of the machine, and when the printing is completed the finger piece 53 is depressed and the work removed from the 120 125 130

machine. During the operation of the handle 38 the full stroke mechanism serves to prevent a reversal of the direction of movement of the handle until the stroke has been completed in either direction, thus insuring a full impression of the work and the return of the handle to its starting position. While the machine is complete, convenient to operate and capable of performing its work efficiently, it is compact and small, and the work parts are simple and few in number.

Having thus described my invention, what I claim as new, and desire to secure by Letters Patent is:—

1. In a printing apparatus, a type drum having fixed on its cylindrical surface a plurality of type forms of various lengths, and movable to bring said forms, selectively, to printing position; a platen, said drum and platen having a relative impressing movement; a plurality of stop shoulders extending in a direction normal to the plane of movement of the carrier, one for each of the type forms and inversely corresponding thereto in length; means for feeding the work; a movable device, said device and shoulders having a fixed relative movement in the direction of extent of the shoulders; a contact part resiliently connected to said device and arranged to be moved by said relative movement of the device and shoulders through distances controlled in extent by contact with said shoulders, said part and shoulders being relatively movable by said selective movement of the carrier to bring them selectively, into co-operative relation, and a connection between said part and feeding means to move the latter an extent proportional to the length of the type form printed.

2. In a printing apparatus, a type carrier movable to bring a plurality of type forms of various lengths, selectively, to printing position; a plurality of stop shoulders extending in a direction normal to the plane of movement of the carrier, one for each of the type forms, and inversely corresponding thereto in length; rotary means engaging the work for feeding the latter; a reciprocating device having a fixed throw in the direction of extent of the stop shoulders; a contact part yieldably movable by said reciprocating device through distances controlled in extent by contact of said part with the stop shoulders, said part and shoulders being relatively movable by said selective movement of the carrier to bring them selectively into co-operative relation; and a connection between said part and rotary feeding means to rotate the latter an extent proportional to the length of the type form printed.

3. In a printing apparatus, a type carrier movable to bring a plurality of type forms

of various lengths, selectively, to printing position; a plurality of stop shoulders extending in a direction normal to the plane of movement of the carrier, one for each of the type forms and inversely corresponding thereto in length; rotary means in engagement with the work for feeding the latter; a reciprocating device having a fixed throw in the direction of extent of the stop shoulders; a contact part yieldably movable by said reciprocating device through distances controlled in extent by contact of said part with the stop shoulders, said shoulders being movable by said selective movement of the carrier to bring them selectively, into co-operative relation with said part; and a pawl and ratchet connection between said part and the feeding means to move the latter an extent proportional to the length of the type form printed.

4. In a printing apparatus, a type carrier movable to bring a plurality of type forms of various lengths, selectively, to printing position; a plurality of stop shoulders, one for each of the type forms and inversely corresponding thereto in length; means for feeding the work; a reciprocating device having a fixed throw in the direction of extent of the stop shoulders; a contact part slidably carried by said reciprocating device to be moved thereby into contact with said stop shoulders, said part and shoulders being relatively movable by the selective movement of the carrier to bring them selectively into co-operative relation; and a resilient connection between said contact part and the work feeding means to move the latter an extent proportional to the length of the type form printed.

5. In a printing apparatus, a type carrier movable to bring a plurality of type forms of various lengths, selectively, to printing position; a plurality of stop shoulders extending in a direction normal to the plane of movement of the carrier, one for each of the type forms and inversely corresponding thereto in length; means for feeding the work; a reciprocating device having a fixed throw in the direction of extent of the stop shoulders; a contact part slidably and resiliently carried by said reciprocating device through distances controlled in extent by contact of said part with the stop shoulders, said shoulders being movable by said selective movement of the carrier to bring them, selectively, into co-operative relation with said part; and a connection between said part and the feeding means to move the latter an extent proportional to the length of the type form printed.

6. In a printing apparatus, a type cylinder having on its cylindrical surface a plurality of type forms of various lengths, and rotatable to bring said forms, selectively, to printing position; a plurality of stop shoulders

- extending parallel with the axis of said carrier, one for each of the type forms and inversely corresponding thereto in length; means for feeding the work; a reciprocating device having a fixed throw in the direction of extent of the shoulders; a contact part yieldably carried by said device through distances controlled in extent by contact with said stop shoulders, said shoulders being movable by said selective movement of the carrier to bring them selectively into cooperative relation with said contact part; and a connection between said contact part and said feeding means to move the latter and feed the work a distance proportional to the length of the type form.
7. In a printing apparatus, a type carrier rotatable to bring a plurality of type forms of various lengths, selectively, to printing position; a gage member adjustable by the selective movement of the carrier and having stop shoulders extending parallel with the axis of the carrier; rotary means for feeding the work; a reciprocating device of fixed throw in a direction parallel with the axis of the carrier; a contact part slidably mounted on said device and movable thereby into contact with the gage through the agency of a spring, and away from the gage through the agency of a positive connection; and a rack and pinion connecting the contact part and the feeding means to rotate the latter an extent proportional to the length of the type form printed.
8. In a printing apparatus, a type cylinder having an open end and rotatable to bring a plurality of type forms of various lengths, selectively, to printing position; a plurality of stop shoulders of various lengths located within said cylinder, one for each of said type forms; means for feeding the work; a reciprocating device of constant throw parallel with the axis of said cylinder; and a contact part yieldably connected with said reciprocating device and adapted to be moved thereby through the end of said cylinder and into contact with the shoulders therewithin; and a connection between said contact device and work feeding means for moving the latter an extent proportional to the length of the type form selected.
9. In a printing apparatus, a type carrier movable to bring a plurality of type forms of various lengths, selectively, to printing position; a gage member adapted to be adjusted by the selective movement of the carrier and provided with horizontally projecting gage shoulders; means for feeding the work; a horizontally reciprocating device; a contact part; means connected with said reciprocating device and operating to move said contact part positively away from said gage shoulders and yieldably into contact therewith; a rack on said contact part, and a pinion coöoperating with said rack and having a pawl and ratchet connection with said work feeding means to operate the latter.
10. In a printing apparatus, a type carrier rotatable to bring a plurality of type forms of various lengths selectively to printing position; a gage member adapted to be adjusted by said selective movement of the carrier; rotary means in engagement with the work for feeding the latter; a rock shaft parallel with the axis of the carrier; a reciprocating device; means connecting said shaft and reciprocating device to impart a fixed throw to the latter parallel with the axis of the carrier by the rocking movement of the shaft; a contact part; means, yieldable in one direction connecting said reciprocating device and said contact part for moving the latter toward and from contact with the gage; and a connection between said contact part and said work feeding means for imparting a variable feeding rotation to the latter.
11. In a printing apparatus, a type carrier rotatable to bring a plurality of type forms of various lengths selectively to printing position; a gage member adapted to be adjusted by said selective movement of the carrier; means for feeding the work; a rock shaft parallel with the axis of the carrier; a reciprocating device; a cam and follower connecting said shaft and reciprocating device for imparting a fixed throw to the latter parallel with the axis of the carrier by the rocking movement of the shaft; a contact part; means yieldable in one direction connecting said reciprocating device and contact part for moving the latter toward and from contact with the gage; and a connection between said contact device and said work feeding means for imparting a variable feeding movement to the latter.
12. In a printing apparatus, a type carrier rotatable to move a plurality of type forms of various lengths selectively to printing position; a gage member having a plurality of stops extending parallel with the axis of said carrier and adapted to be adjusted by the selective movement of the latter; a platen for coöperation with said type forms to impress the work; means for feeding the work; a device adapted for horizontal reciprocating movement; a rock shaft disposed parallel with the axis of said carrier and having a connection with said platen to actuate the latter and also with said reciprocatable device to impart a uniform throw thereto; a contact part having a yieldable connection with said reciprocatable device and adapted to be moved by the latter to and from contact with said gage stops; and a connection between said contact part and work feeding means to impart a variable feeding movement to the latter.

13. In a printing apparatus, a work bed adapted to support commercial paper forms; a casing overhanging said bed; a type carrier in the casing adjustable to bring various type forms of different lengths selectively to position to print the work on said bed; a gage in the casing adjustable with the carrier; a platen below said bed; work feeding means in the casing; a reciprocating device; a contact part adapted to be moved by said device into and out of contact with the gage; a connection between said contact part and said work feeding means; and an operating shaft journaled in the casing and provided with a cam for actuating the platen and also with a cam for actuating said reciprocating device to feed the work a distance proportional to the length of the type form printed.
14. In a printing apparatus, a work bed adapted to support commercial paper forms; a casing overhanging said bed; a cylindrical type carrier in the casing having a plurality of type forms of various lengths fixed on its cylindrical surface with their reading direction parallel with the axis of the carrier; a platen below said bed, said carrier being adjustable to bring said forms selectively above said work bed; a shaft in the casing parallel with the axis of the carrier for moving the carrier and platen relatively into contact; and feeding mechanism in the casing including means to engage and feed the work, a gage adjustable with the carrier, a contact part, a device having a yielding connection with said contact part and adapted to be moved by said shaft parallel with the latter to move said contact part toward and from the gage, and an actuating connection between said contact part and said work feeding means.
15. In a printing apparatus, a work bed adapted to support bank checks and similar paper forms; a casing overhanging said bed; a platen below said bed; a type cylinder in said casing adjustable to selectively position above the platen various type forms of different lengths fixed on the circumference of the cylinder; an operating shaft in the casing for actuating the cylinder and platen relatively into contact; and feeding mechanism in the casing including a gage adjustable with the cylinder, rotary means to engage and feed the work, a contact part, a device adapted to be reciprocated by said operating shaft parallel with the latter to move said contact part toward and from the gage, and a rack and pinion connection between
- said contact part and feeding means to rotate the latter and feed the work.
16. In a printing apparatus, a platen; a type cylinder rotatable about a horizontal axis to bring various type forms of different lengths fixed on its circumference selectively to position above the platen; an operating shaft parallel with the axis of the cylinder for moving the cylinder and platen relatively into contact; a gage on the cylinder; rotary means for feeding the work adapted to engage the latter from above and rotatable about an axis normal to that of the carrier; and a yieldably actuated contact part movable axially of the carrier toward and from said gage and having a geared connection with said feeding means to rotate the latter and feed the work.
17. In a printing apparatus, a platen; a type cylinder rotatable about a horizontal axis to bring various type forms of different lengths fixed on its circumference selectively to position above the platen; an operating shaft parallel with the axis of the cylinder for moving the cylinder and platen relatively into contact; a gage on the cylinder; rotary means for feeding the work adapted to engage the latter from above and rotatable about an axis normal to that of the carrier; means engaging the work from below to hold it in engagement with the feeding means and having a retracting member extending forwardly of the machine for manual operation to release the work; and a yieldably actuated contact part movable axially of the carrier toward and from said gage and having a geared connection with the feeding means.
18. In a printing apparatus, a type carrier having a plurality of word type forms of various lengths on its surface with their reading direction parallel with the axis of the carrier, a platen and means whereby the platen may be operated to take impressions from any desired word form, work feeding devices, gage shoulders movable with the type carrier and extending parallel to the axis of the type carrier, a plunger movable endwise parallel to the axis of the type carrier and to extents determined by the gage shoulders and resilient means for moving same, and connections whereby said plunger drives the work feeding means.

CHARLES G. TIEFEL.
